(57) **CLAIM**

The ornamental design for an eyeglasses frame, as shown and described.

DESCRIPTION

FIG. 1 is a perspective view of an eyeglasses frame showing my new design;

FIG. 2 is a top plan view thereof;

FIG. 3 is a front elevation view thereof;

FIG. 4 is a side elevation view thereof;

FIG. 5 is bottom plan view thereof;

FIG. 6 is a rear elevation view thereof; and,

FIG. 7 is an opposing side elevation view thereof.

The broken lines in the drawings illustrate portions of the article which form no part of the claimed design.
